TUBING SCRAPER FOR OIL WELLS

Carl A. Wettermark, Dale, Tex., assignor, by
mesne assignments, to R. W. Fair, Tyler, Tex.,
and E. A. Kliewer, Longview, Tex.

Application July 23, 1934, Serial No. 736,617
Renewed September 25, 1936

3 Claims. (CL. 166—18)

The present invention relates to an oil well paraffin liquifier for the purpose of cleaning paraffin and other substances that adhere to the tubing in oil wells and the object of the invention resides in the provision of means of this nature which may be interposed in the sucker rod.

Another important object of the invention resides in the provision of a device of this nature which is exceedingly simple in its construction, inexpensive to manufacture, durable, thoroughly efficient and reliable in use and operation, and otherwise well adapted to the purpose for which it is designed.

In the drawing:

Figure 1 is a side elevation of the device embodying the features of my invention, and
Figure 2 is an end elevation thereof.

Referring to the drawing in detail it will be seen that the numeral 5 denotes a shaft preferably constructed of steel and having reduced threaded ends 6. About the shaft 5 are a pair of spaced flat annular flanges 7. Each flange 7 has on opposite sides thereof diagonal vents or grooves 8 in their peripheries. The threaded ends 6 should be standard for engagement with the sucker rods. The flanges should have a diameter about one-eighth of an inch smaller than the diameter of the interior of the tubing. The vents or grooves should be cut at approximately a forty five degree angle to the vertical. These dimensions are merely given as examples of practically tried devices of this nature and I do not care to be limited thereto.

The instrument is to be connected by the threaded ends 6 into a string of oil well sucker rods 9 so that when all the rods are in the well the instrument will work about one hundred feet below the paraffin bottom.

It is thought that the construction, operation, utility and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A device of the class described comprising a shaft having a stationary annular flange thereon intermediate its ends and provided with means at the ends thereof whereby it may be connected and interposed in a string of sucker rods, said flange having grooves formed in the periphery thereof, said grooves being on opposite sides of the flange and arranged at approximate forty five degrees to the vertical.

2. A device of the class described including a shaft having reduced threaded ends and a pair of stationary spaced annular flanges intermediate its ends, said flanges having grooves formed in the peripheries thereof, the grooves of each flange being on opposite sides thereof and being substantially diagonal to the vertical.

3. A paraffin cleaner for oil well flow tubing comprising a shaft equipped with threaded ends adapted for connection between the sections of sucker rods in the well flow tubing, a flat stationary rigid flange rigidly secured to the shaft intermediate its ends and being slightly less in diameter than the diameter of the flow tubing, and the periphery of the flange formed with a groove disposed at an angle with respect to the axis of the shaft.

CARL A. WETTERMARK.
